UNITED STATES PATENT OFFICE

WILLIAM WILSON, OF EAST ORANGE, NEW JERSEY, ASSIGNOR TO WESTERN ELECTRIC COMPANY, INCORPORATED, OF NEW YORK, N. Y., A CORPORATION OF NEW YORK.

ELECTRIC DISCHARGE DEVICE AND OPERATING CIRCUITS THEREFOR.

1,403,726.

Specification of Letters Patent. Patented Jan. 17, 1922.

Application filed March 30, 1918. Serial No. 225,682.

To all whom it may concern:

Be it known that I, WILLIAM WILSON, a subject of the King of Great Britain, residing at East Orange, in the county of Essex and State of New Jersey, have invented certain new and useful Improvements in Electric Discharge Devices and Operating Circuits Therefor, of which the following is a full, clear, concise, and exact description.

10 This invention relates to electric discharge devices and operating circuits therefor which are particularly applicable for use in signaling circuits.

An object of this invention is to provide a novel type of an electric discharge device capable of being employed for repeating or amplifying signals, particularly when selective amplification or repeating is desired.

20 A further object of this invention is to provide a vacuum tube capable of functioning both as an annunciator and as a repeater of electric waves, whereby an impulse impressed on the tube will cause it to be energized so as to function as an annunciator, 25 after which the tube may serve as a repeater of the incoming signals.

As is well known in the art an evacuated vessel of the audion type comprises three electrodes, a filament, an anode and an auxiliary electrode. In one form of this invention, in addition to these electrodes is provided a floating electrode between the auxiliary electrode and the filament, whereby the 35 space current between the filament and the anode is made independent of the static potential, or of slow changes of the potential of the auxiliary electrode of the order of one cycle per second, but is dependent upon rapid changes of the potential of said elec-

40 trode due to voltages of a higher frequency such as voice or radio frequencies. This structure as above described is therefore particularly adapted for a system for the reception of signals, since the space current

45 of the vessel in each arrangement may be varied in accordance with rapidly varying impulses impressed thereon,—that is, its response for such frequencies is quantitative, and so the vessel may be employed as a repeater of incoming signals; and also since

50 the space current is independent of slowly varying impulses,—that is, since the vessel responds qualitatively only to such low fre-

quencies, a vessel having normally zero space current may have its current flow started by a single impulse, which current will continue to flow irrespective of whether other impulses follow the initial impulse, so that the arrangement is also adapted to serve as an annunciator to energize a relay for ringing a bell, for example.

Although this vacuum tube annunciator will hereinafter be described in connection with a receiving station for a high frequency signaling system, it is to be understood that it also may be employed for all other purposes to which an annunciator may be applied.

For the setting of the tube for the annunciator action, the potential of the grid is made just below the critical value for no space current, thereby making the space current substantially zero. An incoming positive impulse of any frequency which would, for instance, be a component part of an incoming signal wave impressed upon the grid will start the space current which will thereafter persist and be independent in value of slow changes of potential of the grid. The current, which is thereby established in the output circuit may be employed to energize a relay for ringing a bell, or to energize any other apparatus desired after the space current flow has been established by an incoming impulse. The same tube when the space current has been established is then in condition to be employed as an amplifier or detector of the incoming signal oscillations, as for rapidly varying oscillations the operation of the tube has been found to be substantially the same as if the floating electrode were absent.

For a better understanding of this invention, reference is made to the following detailed description, taken in connection with the accompanying drawings, in which Fig. 1 shows in detail an evacuated vessel constructed according to this invention; and Fig. 2 shows how this vessel may be employed as a combined annunciator and amplifier in a receiving system.

Fig. 1 shows in perspective an evacuated vessel with certain parts broken away in order that its construction may more readily be understood. In the evacuated vessel in addition to the usual filament 6, anode 7

and control electrode 8, is a fourth electrode 9 which is floating, that is, insulated from the other electrodes 10 and 11 are the leading-in conductors for the filament, and 12 and 13 are the leads respectively for the anode and control electrode. It is to be noted that no leading-in conductor is provided for the floating electrode. Fig. 2 illustrates a receiving system for high-frequency signaling, having in conjunction therewith a vacuum tube annunciator of the general form shown in Fig. 1. Assume that the potential of the source of voltage 16 is sufficient to establish a space current between 15 the anode 7 and the filament 6. If, now, the negative potential of a source of voltage 17 is numerically greater than the critical value for no space current, then, on closing the key 19, the negative voltage applied to 20 the grid will reduce the space current to zero. The tube 5 is then ready to act both as an amplifier and as an annunciator for the signals received by the antenna 20. Assuming that these signals consist of high 25 or radio frequency oscillations, modulated by low or telephone frequency signals, the oscillations received by the transformer 25 will be impressed upon the circuit 26, tuned to the frequency of the carrier wave oscillations. The oscillations in this tuned circuit are then impressed upon the input terminals of a detector 28. The detected currents in the output circuit 29 by transformer 30 may then be impressed upon the input circuit 32 of the tube 5. These detected currents impressed upon the control electrode will make it more positive than the critical value for no space current, thereby allowing the current to flow. After the space current has been started in such a manner by impressing positive impulses on the control electrode, it has been found that the current rises to approximately the value it would have for zero potential of the control electrode, and thereafter remains independent of the value of the static potential of said electrode. The current, however, may be controlled by the rapidly varying impulses resulting from the detection of the incoming signals, so that the tube may function as an amplifier of these impulses.

The space current established in the output circuit 34 by the incoming signals may be employed to energize a relay 35, whereby 55 contact is made between the arm 36 and the point 37, thereby closing the circuit containing battery 39 and the bell 40. The ringing of this bell is, therefore, an indication that signals are being received by the 60 antenna.

The output circuit also contains the detected currents which have been amplified by the tube in a manner now well known in the art. These amplified oscillations may be 65 impressed by the transformer 42 upon other

amplifiers, or as shown, may be impressed upon a suitable receiver 43. As relay 35 presents a path of high impedance for the amplifying currents in the output circuit, a low impedance path containing a condenser 45 is shunted around the relay. 70

In order to sensitize the annunciator for another call, the space current should be brought to zero again. This may be accomplished by opening the key 19 for a short 75 interval of time and then closing it.

The theory of operation of the above described system is not at present well understood. It is probable, however, that the action may be explained on the ground that 80 while the space current is flowing in the tube 5, the floating electrode picks up positive charges of such an amount as to shield the filament from the steady potential of the grid. The thermionic current persists 85 and is thus made independent of the potential between the filament and the control electrode. When, however, the input circuit is opened for an interval of time sufficient to allow these charges to leak off this 90 floating electrode, then, on closing the circuit again, the input electrode will be brought suddenly to a negative potential greater than that required for no space current and the current is reduced before the 95 compensating charges have time to collect on the floating electrode. But as soon as the grid is momentarily made more positive than the critical value, then the space current will start to flow again and the floating electrode will acquire positive charges sufficient to compensate for the static potential between the filament and the grid. 100

The above statements as to the action of the device are the most plausible which at 105 present can be given, but they are not intended in any manner to limit the invention which is defined in the appended claims.

What is claimed is:

1. In an electric system, an electric discharge device having spaced terminals there-in between which space current is adapted to flow, energizing circuits for said device normally closed, said device being normally inoperative, and means comprising an electrical conductor responsive to an impulse impressed on said device to render it operative, while permitting the connections for said circuits to remain fixed. 110

2. In an electric system, an electric discharge device, a source of voltage for said device, energizing circuits for said device normally closed, said device having normally zero space current flowing therein, and metallic means whereby an impulse received 120 by said device establishes said current, while permitting the connections for said circuits to remain fixed.

3. In an electric system, an electric discharge device having an input and an out- 130

put circuit, a source of voltage for said output circuit, said device having normally a given value of space current flowing therein, and means comprising an electrical conductor whereby an impulse received by said device establishes a different value of said space current which persists after said impulse has ceased.

4. In an electric system, an electric discharge device having an input and an output circuit, a source of voltage for said output circuit, said device having normally zero space current flowing therein, and metallic means whereby an impulse received by said device establishes said current which persists after said impulse has ceased.

5. In an electric system, an electric discharge device, a source of voltage for said device, energizing circuits for said device 20 normally closed, said device being normally inoperative, and means comprising an electrical conductor whereby said device is made operative when an impulse is impressed on said device, while permitting the connections 25 for said circuits to remain fixed.

6. The combination with an electric discharge device, of an anode, a cathode and a control element within said device, energizing circuits for said device normally closed 30 and means comprising an electrical conductor whereby said cathode is made independent of slow changes in the potential of said control element, said changes acting merely to cause a sudden rise of current in said 35 device.

7. In an electric system, an electric discharge device having an anode, a cathode and an auxiliary electrode, means for establishing space current between said anode 40 and said cathode, a source of voltage for said auxiliary electrode of sufficient value to reduce said space current to zero, and metallic means operative when said space current is flowing to prevent the static po-

tential of said grid from modifying said 45 space current.

8. The combination with a vacuum tube discharge device which is quantitatively responsive to high frequency variations, of means comprising a floating electrode associated with said device for changing said 50 responsiveness from quantitative in nature to qualitative when the potential variations are of relatively low frequency.

9. In combination, an electric discharge 55 device containing a cathode, an anode, a control electrode and a floating electrode, said floating electrode comprising an apertured screen located between said cathode and said control electrode, and means for 60 maintaining said control electrode and said anode at different potentials with respect to said cathode.

10. In an electric system, an electric discharge device containing an anode, a cathode, a floating electrode, means comprising a fourth electrode for controlling said cathode, an electrical connection between said anode and cathode, an electrical connection between said fourth electrode and said cathode, and means for maintaining said fourth 70 electrode and said anode at different potentials with respect to said cathode.

11. In an electric system, an electric discharge device containing an anode, a cathode, an apertured screen electrode, means comprising a fourth electrode for controlling said cathode, an electrical connection between said fourth electrode and said cathode, said screen electrode being disconnected 80 from said other electrodes, and means for maintaining said anode and said fourth electrode at different potentials with respect to said cathode.

In witness whereof, I hereunto subscribe 85 my name this 26th day of March, A. D., 1918.

WILLIAM WILSON.
